PROTECTIVE DEVICE

Emil Kolisch, New York, N. Y., assignor to Continental Silver Co., Inc., Brooklyn, N. Y., a corporation of New York

Application April 30, 1948, Serial No. 24,233

12 Claims. (Cl. 200—142)

1

This invention relates to protective devices, more especially for electrical appliances of the type used in the home or in the offices of physicians and dentists and particularly to a device which breaks the circuit when the appliance is overheated and may be readily reset to operativeness and, though applicable to heaters for water, liquids or fluids generally, such as for sterilization or for culinary purposes, is shown herein applied to a coffee percolator.

It is among the objects of the invention to provide a protective device for an electrical heating appliance of the above type which is of simple, relatively inexpensive, compact and rugged construction, which does not detract from the normal operation of the appliance, which is not exposed to contact with the materials to be heated by the appliance and which yet may be completely concealed from the exterior of the appliance, which will function to interrupt the circuit upon overheating of the appliance as for instance, in the absence of desired liquid therein, which functions without appreciable arcing both in maintaining the circuit in use and in interrupting the circuit upon overheating, and which admits of being instantly and unerringly restored to operativeness by the unskilled user by resort to a simple manipulation, such as the turn of a knob accessible from the exterior of the appliance and without the need for any tools for disassembly, or for reaching into the interior of the device.

It is a feature of the invention to provide a plurality of fusible links of which one only is maintained in operative position where it is subjected to the heat evolved in the appliance, the remaining fusible links being in reserve for ready replacement upon fusing and rupture of the link in use under excessive heat. To this end the fusible link in action is in engagement with a stop or contact in effective heat conducting and circuit closing relationship with the heating element of the appliance. The stop and the fusible link are relatively displaceable, preferably by a manual member accessible from the exterior, such as for instance from the bottom of the appliance, for readily replacing a fused link with a reserve link. Preferably each link is mounted on a support and the stop has associated therewith a resilient member which, when the link engages the stop is stressed, thereby to force the stop against the link to exert pressure thereagainst, so that upon softening of the fusible link in action under excessive heat, the latter will readily be ruptured to sever the link and cause disengagement from the stop thereby to

2

break the circuit. In a preferred construction, the fusible links radiate from a rotatable mount which desirably rises from the bottom of the device and to which is affixed the manually operated knob, while the stop is affixed thereto with its associated resilient member.

Another feature of the invention is the provision of means on the rotatable mount to enable it to rotate only in one direction, thereby 10 ensuring that the link will properly engage the stop so that positive electric contact will be made.

This application is a continuation in part of my copending application, Serial No. 767,696, filed August 9, 1947.

15 In the accompanying drawings in which are shown one or more of various possible embodiments of the several features of the invention,

Fig. 1 is a longitudinal cross sectional view of the electrical appliance with parts broken away,

20 Fig. 2 is a transverse cross sectional view taken along line 2—2 of Fig. 1,

Fig. 3 is a longitudinal cross sectional view taken along line 3—3 of Fig. 1,

Fig. 4 is a detail perspective view on a larger 25 scale of the fusible link and support therefor, and

Fig. 5 is a bottom view of the heater housing.

Referring now to the drawings there is shown a preferred embodiment of the protective device as applied to a coffee percolator 10. The latter comprises a container 11 affixed as by welding as at 12, to a hollow base 13 which has an annular flange 14 at the bottom thereof affixed to the bottom rim 15 of the base by rivets 16. A bottom plate 17 is affixed to said flange 14 by means of screws 18 which also mount legs 19 and which pass through the bottom plate 17 and are threaded into corresponding openings 21 in the flange 14.

Carried by the top 25 of the base 13 and extending through an opening 26 therein is a generally cylindrical, preferably ceramic mount 27. A cylindrical protective housing 28 encompasses that portion of the mount which protrudes above top 25 and has an inturned rim 29 extending under diametrically opposed laterally extending ears 31 integral with the mount 27. To permit assembly of the housing 28 to the mount, the rim 29 may have diametrically opposed slots 32 to accommodate said ears 31 so that upon slight rotation of the housing 28, after introduction of the ears into the slots 32, the housing is attached relative to the mount. A nut 33 secured upon the threaded lower end 34 of the mount 27 causes the ears 31 to be pressed against the

inturned rim 29 of the housing, rigidly to clamp the housing and the mount to the base.

A high resistance wire 35 is wound around the upper end 36 of the mount 27 which is of slightly reduced diameter forming an annular ledge 37. One end 38 of the wire is connected to the head of a bolt 39 which extends through a bore 41 in the ledge 37 and the mount 27, and protrudes from the bottom of the mount as at 42, being retained therein by a nut 43. The other end 44 of the resistance wire 35 passes through a bore 45 in the ledge 37 and mount 27 and extends from the bottom of the mount as at 46 and is connected by a lead 47 to a terminal plug 48 rigidly affixed to the wall of the base 13 and insulated therefrom by insulating washers 49, as is the companion terminal plug 51.

The protective device disposed within the hollow base 13 establishes an electric circuit from the two ends 38 and 44 of the heating coil to the two terminals 48 and 51, respectively. The device includes a plurality of fusible links 54, each carried by a corresponding support 55. An electrical contact closes circuit to one only of said links. The rupture of the fusible link under excessive heat results in automatic interruption of the electric circuit, preferably under release of stress resiliently imposed in operative position. The contact and the fusible links are then relatively displaceable by manual action to restore the circuit. It is, of course, not necessary that the entire length of the link be of fusible material but only a portion thereof need be in order to break the circuit when such fusible portion ruptures.

The embodiment of the protective device herein chosen to illustrate my invention comprises a substantially L-shaped bracket 56 of heat conducting metal such as sheet metal, having laterally extending ears 57 and 57' on the side edges respectively of its downwardly extending arm 58 and with its transverse arm 59 extending at substantially right angles to arm 58 and affixed to the bottom end 42 of bolt 39 by nut 43, as shown in Fig. 3.

Pivottally mounted on arm 58, as by a nut 61 and bolt 62, is a stop or contact preferably in the form of a metal finger 63 having a laterally projecting hook 64 at the end thereof. By means of a tensed spring 65 about bolt 62 which coacts at one end with ear 57, as at 66, and at its other end with the rear edge of finger 63, as at 67, the finger is normally urged about the pivot toward ear 57' which limits rotation of said finger.

Mounted within the base on the upper face 71 of a substantially circular flat domed portion 72 formed in the bottom plate 13, is a substantially U-shaped bracket 74, having laterally extending arms 75 which are affixed to face 71 by rivets 76. Extending through an opening 77 in the cross piece 78 of bracket 74, and through an axial opening 79 in the face 71 of the bottom plate 13, is a shaft 81 having a flange 82 integral therewith and seated on the cross piece 78. A collar 83 is affixed on shaft 81 beneath cross piece 78 by a set screw 84 securely, yet rotatably to support the shaft on bracket 74.

Carried on the shaft is a mount 80 comprising a disc 85 of insulating material mounted at its axis on the upper part 86 of shaft 81, as is a generally circular metal contact plate 87 positioned on said disc 85 and which has a hub 88 of insulating material through which said upper part 86 extends.

Plate 87 has a plurality of radiating slots 90,

therethrough illustratively six in number, through each of which extend the arms 89 of the substantially L-shaped bracket or support 55, base 92 of which extends at right angles to arms 89 and is sandwiched between disc 85 and plate 87, and in electrical contact with the latter. By means of a nut 93 threaded on the end 86 of shaft 81, the plate and disc are tightly clamped together against flange 82, thereby rigidly clamping the bases 92 of supports 55 therebetween, securely to retain arms 89 in upright position.

In order to provide a convenient means for rotating the mount 80 from the exterior of the base, the end of the shaft 81 which extends through opening 79 in the bottom plate has a knob 95 affixed thereon by a set screw 96, the legs 19 of the base and the dome 72 affording clearance for said knob when the appliance 10 is placed on a table.

The upper ends of each pair of arms 89 are bent over a fusible link 54 securely to hold the latter parallel to and radially of the plate 87 and aligned with the contact finger 63 so that the latter will be in the substantially circular path of the links and when the mount is rotated, the links will successively abut against said contact finger.

Also affixed on face 71 is an L-shaped bracket 98, the upstanding arm 99 of which has affixed thereto an insulating block 101, which carries a laterally extending resilient contact arm 102 affixed thereon by screws 103 and which is in electrical contact at its free end 104 with the rim of contact plate 87. In order to limit the rotation of mount 80 to one direction only, the rim of the plate 87 is provided with a plurality of ratchet teeth 105 which coact with the end 104 of contact arm 102 urged thereagainst by reason of the resiliency of said arm and which functions as a ratchet pawl.

In order to complete the electrical circuit, screw 103 is connected by lead 107 to terminal 51 on the wall of the base.

With a link 54 against stop 63, as shown in Figs. 1, 2 and 3, the container 11 is filled with liquid and a source of current is applied to terminal plugs 48 and 51. The circuit is from terminal plug 48, lead 47, heating element 35, bolt 39, bracket 56, stop finger 63, link 54, support 55, metal carrier plate 87, contact arm 102 and lead 107 to terminal 51. Since a good heat conducting path is established from the source of heat to the stop finger 63, overheating (as for instance in the absence of liquid) will cause the engaged link 54 to soften. Before the fusible link melts, its mechanical strength will have been so greatly reduced that the tension of the spring urged stop finger 63 will exert sufficient pressure against the link quickly to shear the latter, as the stop finger 63 rotates on its pivot thereby breaking the circuit so rapidly that there is no danger of arcing.

But for this mechanical shearing action, if the user should cut off the electric current when the fusible link had just begun to soften and had been deformed from its original shape, it would remain in this deformed condition when the apparatus was permitted to cool to normal temperature. The deformity of the link might cause only slight contact to be made between the link and the stop finger 63, resulting in a high resistance joint which, upon passage of current therethrough upon further use of the appliance, might cause sufficient heat to develop at the point of contact to melt the link even though

the container was full of water and the appliance operating normally.

As the links other than the one in operation, are not in contact with any heat conducting metal such as the stop 63, although the temperature in the base will rise due to overheating in container 11, this rise will not be sufficient to weaken them before the circuit is broken by the rupture of the link in operative position.

The user, noticing that the device is not operating, will turn knob 95 to again complete the heating circuit. As the link that formerly had been against stop finger 63 has been sheared, there is nothing to impede the counter-clockwise rotation of the knob 95, as shown in Fig. 2.

When the knob is turned in a counterclockwise direction, link 54 will first abut against the hook end 64 of the stop finger 63. As the knob is rotated further, the link will pivot the stop finger 63 until the rear edge of the latter abuts against ear 57, in which position spring 65 will be in highly tensed condition. It is to be noted that with stop finger 63 exerting pressure against link 54 and as the end 194 of contact arm 102 is in engagement with one of the teeth 105 on the periphery of plate 87, a positive contact will be made between the link 54 and the stop finger 63 that will not jar loose.

Thus by the device hereinabove described, an efficient protective device is provided that will positively break the circuit in the event of any overheating, yet can quickly and simply be adjusted to restore the appliance to operative condition without the need for special skill or any tools.

When all the fusible links have been melted, it is a relatively simple matter to remove the bottom plate 11 by unloosing screws 18. The entire carrier unit or mount 80 can then be replaced by a new unit or the plate 87 can be removed from disc 85 by removing nut 93 whereupon the link carrying supports can be withdrawn from slots 90 and replaced.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A protective device for electric heating appliances, said device comprising a mount having a plurality of supports thereon, a fusible link carried by each of said supports and extending radially of said mount, a contact stop engaged by one of said links and maintaining the corresponding support in circuit, means to maintain a pressure of the contact stop at substantially right angles against the engaged link whereby upon weakening of said link, the contact stop will rupture the latter to break the circuit, and means after rupture of said engaged link to bring the next fusible link into engagement with said contact stop.

2. A protective device for electric heating appliances, said device comprising a rotatable mount, a plurality of supports rotatable with said mount, a fusible link carried by each of said supports and extending radially of said mount, a contact stop of heat conducting material engaged by one of said links and maintaining the corre-

sponding support in circuit, means upon weakening of the engaged link to rupture the latter, and means after rupture of the engaged link to bring the next fusible link into engagement with said contact stop, said rupturing means exerting pressure against said link at substantially right angles thereto.

3. A resettable protective device for electric heating appliances, said device comprising a manually rotatable mount, a plurality of supports rigid with said mount, a fusible link carried by each of said supports, a pivoted, stressed contact finger of heat conducting material engaged by one of said links and maintaining the corresponding support in circuit, and means successively to bring said links into engagement with said pivoted contact finger and to stress the latter, whereby upon weakening of the engaged link, the stressed finger will pivot to rupture said link, thereby to break the circuit.

4. A resettable protective device for electric heating appliances, said device comprising a rotatable insulating disc, a generally circular contact making element affixed to said disc, a plurality of supports rigid with said element and said disc and rotatable therewith, a fusible link at the end of each of said supports, a contact of heat conducting material engaged by one of said links and maintaining the corresponding support in circuit, stressed resilient means urging said contact against said link whereby upon weakening of the engaged link, the latter will be ruptured and said resilient means unstressed, and means successively to bring said links into engagement with said contact and to stress said resilient means.

5. A resettable protective device for electric heating appliances, said device comprising a rotatable insulating disc, a plate affixed to said disc, a plurality of radially positioned supports rigid with said plate and said disc and rotatable therewith, a fusible link carried by each of said supports, a pivoted contact finger of heat conducting material in the path of rotation of said links, engaged by one of said links and maintaining the corresponding support in circuit, stressed resilient means urging said pivoted contact finger against said link, whereby upon weakening of the engaged link the latter will be ruptured and said resilient means unstressed, and means successively to bring said links into engagement with said contact finger and to stress said resilient means.

6. A resettable protective device for electric heating appliances, said device comprising a rotatable insulating disc, a generally circular metal contact plate rigid with said disc and having a plurality of radiating slots therein, a plurality of metal brackets clamped between said disc and said plate and extending respectively through said slots, a fusible link at the extending end of each of said brackets, a pivoted contact finger of heat conducting metal in the path of rotation of said fusible links, means resiliently urged against the rim of said carrier to make contact therewith, stressed resilient means urging said pivoted contact finger against said link, whereby upon weakening of the engaged link the latter will be ruptured, thereby to break the circuit and unstress said resilient means, means to rotate said disc and said plate, thereby successively to bring each of said links into contact with said contact finger and to stress said resilient means, and ratchet means to limit the direction of rotation of said disc and said plate.

7. A resettable protective device for an electric heating appliance, said device comprising an insulating disc rotatably mounted on said bottom plate, a generally circular contact making element rigid with said disc and rotatable therewith, a plurality of brackets rigid with said disc and element and rising therefrom, a fusible link on each of said brackets, a contact finger in the path of rotation of said fusible links, and a contact arm having its free end resiliently urged against the rim of said element to make contact therewith.

8. A resettable protective device for an electric heating appliance, said device comprising an insulating disc, a generally circular contact making plate affixed to said disc and having a plurality of radiating slots therein, means rigid with said disc for manually rotating said disc and said contact plate, a resilient arm coacting with said contact plate to limit the rotation thereof, a plurality of substantially L-shaped brackets clamped between said disc and said contact plate and respectively rising upwardly through the slots in said contact plate, a fusible link affixed to the free end of each of said brackets, and a pivoted contact finger in the path of rotation of said fusible links successively to engage the latter as said disc and said carrier are rotated.

9. The combination set forth in claim 8, in which said contact plate has a plurality of ratchet teeth on the rim thereof and said resilient arm has a pawl at the end thereof in engagement with said ratchet teeth, to limit the rotation of said contact plate.

10. A resettable protective device for an electric heating appliance, said device comprising a bracket, a depending contact finger pivoted to said bracket, an insulating disc, a metal contact plate affixed to said disc, means rigid with said disc for manually rotating said disc and said contact plate, a plurality of brackets rigid with said contact plate and rising upwardly therefrom, a fusible link affixed to the end of each of said brackets, the path of rotation of said brackets and said links causing said links successively to abut against said contact finger, resilient means urging said contact finger against said links, and

8
a contact arm having its free end urged against the rim of said contact plate.

11. A resettable protective device for electric heating appliances, said device comprising a rotatable mount including an insulating disc, a generally circular contact making element superposed thereon, means rigidly clamping said contact element and said disc together, fuse link carrying elements rising from said contact element, a fusible link at the end of each of said carrying elements, a contact of heat conducting material engaged by one of said links pressing thereagainst and maintaining the corresponding carrying elements in circuit, whereby upon weakening of the engaged link the latter will be ruptured, means successively to bring said links into engagement with said contact, said rotatable mount having peripheral ratchet teeth and coacting pawl means for limiting the rotation of said mount in one direction.

12. A resettable protective device for an electric heating appliance of the type having a heating element, said device comprising a rotatable insulating disc, a generally circular metal contact plate rigid with said disc and having a plurality of radiating slots therein, a plurality of brackets clamped between said disc and said plate and extending respectively through said slots, a fusible link at the extending end of each of said brackets, a contact finger of heat conducting metal in electrical circuit with said heating element and in the path of rotation of said fusible links, means to rotate said disc and said plate, thereby successively to bring each of said links into contact with said contact finger, and resilient means to retain said contact finger and said link in engagement.
